PUMP

Filed May 9, 1925

Charles W. G. Allender

By Watson E. Coleman
Attorney

UNITED STATES PATENT OFFICE.

CHARLES W. G. ALLENDER, OF STEAMBOAT SPRINGS, COLORADO.

PUMP.

Application filed May 9, 1925. Serial No. 29,245.

To all whom it may concern:

Be it known that I, CHARLES W. G. ALLENDER, a citizen of the United States, residing at Steamboat Springs, in the county 5 of Routt and State of Colorado, have invented certain new and useful Improvements in Pumps, of which the following is a specification, reference being had to the accompanying drawings.

This invention relates to certain improvements in pumps and has relation more particularly to a device of this general character commonly known as "plumber's friend," and an object of the invention is to provide 15 a device of this kind which may be employed to advantage in removing obstructions within pipes associated with a wash basin, toilet or the like.

It is another object of the invention to 20 provide a device of this general character including a handle member which also constitutes a pump proper.

The invention consists in the details of construction and in the combination and 25 arrangement of the several parts of my improved pump whereby certain important advantages are attained and the device rendered simpler, less expensive and otherwise more convenient and advantageous for use, 30 as will be hereinafter more fully set forth.

The novel features of my invention will hereinafter be definitely claimed.

In order that my invention may be the 35 better understood, I will now proceed to describe the same with reference to the accompanying drawings, wherein:—

Figure 1 is a view in perspective illustrating a pump constructed in accordance with an embodiment of my invention;

Figure 2 is an enlarged sectional view 40 taken longitudinally through the device as illustrated in Figure 1;

Figure 3 is a view in bottom plan of the device as illustrated in Figure 1;

Figure 4 is a fragmentary view partly in 45 section and partly in elevation of the pump piston and the rod connected therewith;

Figure 5 is a fragmentary view in perspective of the sleeve or bushing insertible within the pump cylinder provided in the handle;

Figure 6 is a view in perspective of the lower or inner end portion of the handle.

As disclosed in the accompanying drawings, C denotes a cup-like member substantially concavo convex in form and which has

its peripheral portion defined by an outstanding flange 1. This cup C is preferably formed of suitable rubber compound. The axial center of the cup C is provided with a port 2 and extending outwardly from said central portion of the cup C and concentric to the opening 2 is an elongated tube or neck 3 preferably integrally formed with the cup C. The wall of the tube or neck 3 at a point closely adjacent to its junction with the cup C is provided therethrough with an air inlet 4, outward flow through said inlet 4 being prevented by a flap valve 5 suitably attached to the inner 60 face of the wall of the sleeve 3.

Snugly insertible within the tube or neck 3 is an end portion of an elongated handle member H of wood or other preferred material, said inserted or inner end portion of the handle member H being provided with an elongated recess or bore 6 whereby said end portion of the handle member H constitutes a cylinder. The handle member H when inserted within the tube or neck 3 has 70 its inserted end substantially in contact with the central portion of the cup C and said inserted or outer end of the bore 6 is open so that the port 2 affords direct communication between the chamber or cell 7 of the cup C and the bore 6. The wall of the bore or cylinder 6 at the inner or inserted end portion thereof is provided with a cut out portion or recess 8 which is adapted to register with the port 4 so that said port 4 will 75 have ready communication with the bore or cylinder 6 and said cut out portion or recess 8 is of such dimensions to afford no hindrance or obstruction to the requisite functioning of the flap valve 5.

I also prefer to snugly engage within the bore or cylinder 6 a sleeve or bushing 9 the outer end of which being defined by an outstanding flange 10 which overlies the inner or inserted end of the handle member H 80 and said sleeve or bushing 9 is provided in its wall with the cut out portion or recess 11 which registers with the cut out portion or recess 8 in the wall of the bore or cylinder 6.

The applied sleeve or bushing 9 provides 105 a liner for the bore or cylinder 6 whereby the efficiency of the sleeve is materially increased particularly when the handle member H is formed of wood. This sleeve or bushing 9 operates effectively to prevent undue swelling of the wall of the bore or cylinder 6 and also permits the handle

member H to be produced from a low grade of wood.

Working within the bore or cylinder 6 is a piston P of desired dimensions and of preferred material, said piston having axially disposed therethrough an end portion of a rod 12, said rod being firmly attached to the piston P by the nuts 14 threaded on the rod 12 above and below the piston P. It is preferred that inwardly of each of the nuts 14 there be provided a washer 15. The upper nut 14 and washer 15 also operate to hold in desired position with respect to the piston P the leather cup 16 which has direct contact with the inner side wall of the bore or cylinder 6 or more particularly the applied sleeve or bushing 9.

The rod 12 extends freely through the axial center of the handle member H and has its outer end secured or clamped to the knob 17 by the nuts 18 threaded on said rod and contacting with the knob 17 from above and below.

When the piston P is retracted by pull upon the knob 17 air will be drawn into the bore or cylinder 6 in advance of the piston P and at the same time flow will be closed through the port 2 by the flap valve 19 fixed to the inner face of the cup C. As the piston is moved forwardly, as by pressure upon the knob 17, flow through the port 4 will be closed and the air will be forced within the cup-like member C through the port 2 and as said cup-like member C is properly positioned with respect to the pipe to be opened, the resultant air pressure will effect the desired removal of the hindrance or obstruction within such pipe.

As is particularly illustrated in Figure 2 of the drawings, it is to be noted that as the piston P moves towards the member 7 it is prevented from passing over the cut out portion or recess 8 by contact of the knob 17 with the outer end of the handle H. This assures the piston being in the most effective position when outward pull is imposed thereon.

From the foregoing description it is

thought to be obvious that a pump constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

A pump of the class described comprising, in combination, a cup-like member having a port through its central portion, an outstanding neck carried by the central portion and surrounding the port, a flap valve secured within cup-like member for closing flow through the port, a handle having an end portion insertible within the neck, said inserted portion of the handle being provided with a bore open at its outer end so that the port in the cup-like member affords direct communication between the chamber 75 of the cup-like member and the bore of the handle, a piston working within the bore of the handle, an operating rod for the piston extending freely through the handle, and an operating knob carried by the outer end 80 portion of the rod, the inserted end of the handle having a cut out portion affording communication with the bore of said handle, the wall of the neck being provided with a restricted port adapted to communicate with 85 the cut out portion of the handle, the knob carried by the rod contacting with the outer end of the handle to stop the movement of the piston in a direction toward the cup-like member before the same passes over the cut 90 out portion in the inserted end portion of the handle.

In testimony whereof I hereunto affix my signature.

CHARLES W. G. ALLENDER.
